UNITED STATES PATENT OFFICE.

EDWARD L. MATHISON, OF PANORA, IOWA.

RURAL-MAIL-CARRIER'S CABINET.

No. 874,896.

Specification of Letters Patent.

Patented Dec. 24, 1907.

Application filed April 18, 1907. Serial No. 368,841.

To all whom it may concern:

Be it known that I, EDWARD L. MATHISON, a citizen of the United States, residing at Panora, in the county of Guthrie and State 5 of Iowa, have invented a certain new and useful Rural-Mail-Carrier's Cabinet, of which the following is a specification.

The object of my invention is to provide a cabinet of simple, durable and inexpensive 10 construction, and of compact arrangement, designed to contain money order pads, envelop compartments, a folding writing desk and a cash holder, so arranged as to be especially adapted for use by rural mail carriers 15 in facilitating their work in preparing money orders, making change, and carrying envelopes, postals, and the like.

My invention consists in the construction, arrangement and combination of the various 20 parts of the cabinet, whereby the objects contemplated are attained, as hereinafter more fully set forth, pointed out in my claims and illustrated in the accompanying drawings, in which—

25 Figure 1 shows a plan view of the complete cabinet embodying my invention, with the cover open, and the folding writing table also open. Fig. 2 shows a transverse, sectional view taken on a line through the center of the cash holder, taken in a position for writing, and Fig. 3 shows a central, transverse sectional view, in a folded position.

Referring to the accompanying drawings, I have used the reference numeral 10 to indicate 35 the body of the cabinet, which comprises a bottom, sides and ends arranged in rectangular form. Hinged to the top of the rear side of the body is a cover 11. A clasp 12 of the ordinary construction is provided 40 for holding the cover to the body portion. A handle 13 is fixed to the front side of the cabinet to provide for carrying it. Hinged to the top of the rear side of the cabinet, within the cover 11, is a tray 14, having notches 15 formed in its end portions, near its forward side. Hinged to the forward side of the tray is a writing table 16, normally folded into the notches 15, so that its top is flush with the top of the tray, and its bottom slightly 45 spaced apart from the bottom of the tray, and in its extended position, it projects outwardly to form a hand support for a person writing upon a tablet or money order blank, placed within the tray, said tray being of a 50 size and shape to contain a stamp book and a money order pad side by side, which will oc-

cupy the space between the writing table 16 and the bottom of the tray, when said writing table is in its folded position.

Arranged within the body portion 10 are 60 two longitudinal partitions 17, secured to the ends of the body portion, and spaced apart slightly from the sides thereof, thus forming two compartments to receive a register receipt book, and a money order receipt book. 65 Arranged near one end of the body portion is a transverse partition 18, with its ends connected with the partitions 17. The space between the partition 18 and the adjacent end of the body portion 10 is designed to 70 form a currency holder 19.

I have provided a receptacle for small change normally resting in the upper portion of the currency holder, which receptacle is preferably formed complete of a single 75 piece of metal, and comprises a bottom 20, sides and ends 21, and a top 22, which extends from the rear about half way across the top, thus permitting the operator to insert his fingers between the end of the top 80 and the adjacent portion of the front 21. This coin receptacle is connected by a hinge 23 with the partition 17 at the rear of the body portion 10, its forward end normally resting on top of the partition 17 at the 85 front of the body portion, as shown in Fig. 2. In the space between the partition 18 and the end of the body portion 10, opposite from the cash holder, are three longitudinal partitions 14, forming between them and the 90 partitions 17 four compartments for small envelopes and the like.

In practical use, the rural mail carrier first equips the cabinet with a quantity of change in the hinged coin receptacle, and a quantity 95 of currency in the holder 19. He also provides receipt books in the compartments prepared for them, with small envelopes in the proper compartments, and money order applications and stamp book in the hinged 100 tray. The entire device will then occupy a very small space, and may be carried by the handle 13. Assuming that he desires to prepare a money order, he first opens the cover 11, and throws back the writing table 16, 105 then his hand may be supported on the writing table while writing upon the money order pad contained within the tray. If he desires to make change, he may readily reach the small coin by first folding up the writing 110 table 16, and then turning the tray 14 rearwardly over the cover 11, as shown in Fig.

1, whereupon the coins in the coin receptacle are readily accessible to him. If he desires to obtain any article within the holder 19, the coin receptacle is turned rearwardly 5 on its hinges to an upwardly and rearwardly inclined position, and the coins will be retained in the receptacle on account of the cover 22. In this way, there is no danger of loss or misplacement of any of the articles 10 which it is necessary for the rural mail carrier to provide himself with, and all of the operations which he is usually required to make in connection with his duties may be performed readily and easily by the use of 15 this cabinet.

Having thus described my invention, what I claim and desire to secure by Letters Patent of the United States therefor is—

1. In a device of the class described, the 20 combination of a box shaped portion, a hinged cover, a tray hinged to the box shaped body portion, and having a writing table hinged to the top of the tray, and capable of being extended to position, projecting forwardly from the front of the tray.

2. In a device of the class described, the 25 combination of a box shaped body portion, a hinged cover, a coin receptacle open only at the forward portion of its top surface, and hinged at its rear end, and having its front end normally resting upon a stationary support, to hold the tray in a horizontal position.

3. In a device of the class described, the 30 combination of a box shaped body portion, a hinged cover, two longitudinal partitions arranged near the front and rear of the box, a transverse partition between said longitudinal partitions near one end, a coin receptacle open only at the forward portion of its

40 top, hinged at its rear end to one of the longitudinal partitions, and contained between the transverse partitions and the adjacent end of the box, said coin receptacle being of such depth as to leave a large receptacle beneath it, and a series of longitudinal partitions extending from the transverse partitions to the end of the box opposite from the coin receptacle.

4. A rural mail carriers' cabinet comprising a box shaped body portion, a hinged cover therefor, a tray hinged to the rear of the box shaped body, with its forward end resting on the front of the box shaped body, said tray formed with notches in the forward portions of the ends thereof, a writing table hinged to the front side of the tray, normally resting in said notches, and spaced apart from the bottom of the tray, and capable of being extended forwardly beyond the tray, to form a long support, two longitudinal partitions within the box shaped body, beneath the tray, a transverse partition extended between the longitudinal partitions near one end thereof, a coin holder in the upper portions of the receptacle, formed by 55 said partitions, said coin holder open only at the forward portion of its top, hinged at its rear end to the longitudinal partition, and having its forward end resting upon the other longitudinal partition, and a series of 60 short longitudinal partitions extended from the transverse partition to the end of the box shaped body, opposite from the coin receptacle.

EDWARD L. MATHISON.
